Primary Examiner — Mehri F Bajoul*(74) Attorney, Agent, or Firm* — Lewellyn Law, PLLC;
Stephen Lewellyn(57) **CLAIM**

The ornamental design for a game net, as shown and described.

DESCRIPTION

FIG. 1 is a top perspective view of the game net showing our new design;

FIG. 2 is a bottom perspective view thereof;

FIG. 3 is a top plan view thereof;

FIG. 4 is a bottom plan view thereof;

FIG. 5 is a side elevation view thereof, the opposite side being a mirror image; and,

FIG. 6 is a front elevation view thereof, the opposite side being a mirror image.

The dashed lines in FIGS. 1-6 are included for the purpose of illustrating portions of the game net that form no part of the claim.
